UNITED STATES PATENT OFFICE.

LAURA H. HILL, OF SEATTLE, WASHINGTON.

LIFE-RAFT.

1,283,766.

Specification of Letters Patent.

Patented Nov. 5, 1918.

Application filed March 4, 1918. Serial No. 220,183.

To all whom it may concern:

Be it known that I, LAURA H. HILL, a citizen of the United States, and resident of the city of Seattle, county of King, and State of Washington, have invented certain new and useful Improvements in Life-Rafts, of which the following is a specification.

My invention relates to life rafts and consists of a raft which is so constructed that it may be pitched into the water, either side up, and may then have the upper side opened up so as to form a cage or box-like structure into which people may get and which is also provided with means for the storage 15 of necessary supplies.

The object of my invention is to provide a raft which shall be capacious in its provision of space for people who are using it, and which may also be made safe so that 20 there is no danger of people being washed therefrom. Other objects of my invention will appear from a study of the specification and the claims.

In the accompanying drawings I have 25 shown the preferred manner of constructing my device.

Figure 1 is a plan view of the raft, one of the shutters being shown in closed position and the other in opened position.

30 Fig. 2 is a cross section taken on the line 2-2 of Fig. 1.

The chief flotation elements of this raft consist of two cylinders 1, as herein shown composed of sheet metal. In addition there 35 are some small cylinders 10, one at each end, which, in addition to serving as flotation elements, are also provided with caps 11 at the upper and at the lower sides thereof, these being removable and thus enabling the 40 interior of these cylinders to be used as receptacles for supplies. The provision of the cap at both top and bottom side, results in having a cap in convenient position for removal whichever side up the raft may float.

45 Both the cylinders 1 and 10 are shown as having conical ends. This is merely a matter of convenience of construction.

The frame which holds these flotation cylinders in position has transverse bars 2 50 which embrace the cylinders 1 at top and bottom. It also comprises longitudinal bars 20 which are placed across the bars 2 and also just inside of the cylinders 1. Bars 21, which connect the outer ends of the bars 2 55 serve to secure the cylinders in the frame. The frame is also provided with transverse

bars 22 at each end and with boards 23 which are adapted to act as seat boards or foot rests, each approximately on the central plane of the cylinders 1.

The space included between the two cylinders 1 is covered by two swinging grates or shutters 3, at each side of the raft. These shutters are hinged at their outer edges, namely, at the points 30, upon bars 31 which extend lengthwise of the raft and may swing either inward, so as to cover the space between the floats 1, or outward, so as to give a broader upper surface. In Fig. 1, one of these shutters is shown as swung outward 70 and the other as swung inward.

Hinges 32 of ordinary character may be employed, but I prefer to employ securing means consisting of a rope 4 which is wound about one of the side bars of the shutter 75 and the bar 31 of the frame, as is clearly shown in Fig. 1. With this used, the hinges 32 may, if desired, be dispensed with. A central bar 33 may be employed extending lengthwise of the raft and centrally thereof, 80 to which the swinging edges of the shutters may be lashed by a rope or otherwise secured, as desired.

The construction, in so far as the provision of shutters and the manner of securing 85 these, is alike for both sides of the raft. In consequence, when the raft is thrown into the water it is immaterial which side thereof comes uppermost. The lashings of the upper shutters 3 may be cut and the shutters swung outward. The shutters of the lower side then serve as a floor to prevent any one from slipping through. In this condition the board 23 may serve, either as a seat board or as a support for the feet, 90 in which latter case the upper bar 31 and the adjacent portions of the shutter 3 will serve as a seat. The shutters may be secured in their closed position by means of a rope, as is shown at 5 in Fig. 1. 100

What I claim as my invention is:

1. A life raft comprising two floats, a frame securing said floats in separated position, a pair of shutter frames at each side of the raft adapted together to cover the 105 space between the floats, said shutter frames being hinged along their outer side edges to swing outward and over the floats.

2. A life raft comprising a series of floats, certain of said floats having removable caps 110 at top and at bottom sides thereof, a frame holding said floats bordering a central area,

shutters at both sides of the raft hinged along their outer side edges to swing over the floats, and means for normally holding said shutters swung inward.

5 3. A life raft comprising floats, a frame holding said floats separated and having seat boards just within the floats and substantially in the axial plane of the floats, said frame also having bars extending 10 lengthwise of the floats and at opposite sides

of the frame, and shutters hinged to said bars and adapted when swung inwardly to cover the space between the floats and to swing outwardly over the floats, and means for securing said shutters when swung inwardly.

Signed at Seattle, Washington, this 25th day of February 1918.

LAURA H. HILL.
